KNIFE

Henry Vossler, Providence, R. I., assignor to Imperial Knife Company, Inc., Providence, R. I., a corporation of Rhode Island

Application January 13, 1948, Serial No. 2,079

9 Claims. (Cl. 30—155)

1

This invention relates to knives, and, more particularly, pertains to improved pre-assembled ornamental covering units for knife frames of the type shown, described and claimed in U. S. Letters Patent No. 2,231,783, issued May 5, 1942.

It is an object of the present invention to provide ornamental covering units of the character described which are more rugged and durable than the units shown in said earlier patent.

It is another object of this invention to provide ornamental covering units of the character described which, despite their increased strength and life, are but little, if any, more expensive to make than the units illustrated in said earlier patent.

It is an additional object of this invention to provide ornamental covering units of the character described which are capable of maintaining their proper assembled position on knife frames throughout long and hard use.

Other objects of this invention will in part be obvious and in part be pointed out hereinafter.

The invention accordingly consists in the features of construction, combinations of elements and arrangements of parts which will be exemplified in the constructions hereinafter described, and of which the scope of application will be indicated in the appended claims.

In the accompanying drawings in which are shown various possible embodiments of my invention,

Fig. 1 is a side view of a jackknife having a covering unit embodying my invention;

Fig. 2 is an end view of the knife shown in Fig. 1;

Fig. 3 is a plan view of the under-surface of the preassembled covering unit;

Fig. 4 is a sectional view taken substantially along the line 4—4 of Fig. 3;

Fig. 5 is a sectional view taken substantially along the line 5—5 of Fig. 1;

Fig. 6 is a sectional view taken substantially along the line 6—6 of Fig. 5;

Fig. 7 is a view similar to Fig. 3 of a covering unit embodying another modified form of my invention;

Figs. 8 and 9 are sectional views taken substantially along the lines 8—8 and 9—9, respectively, of Fig. 7;

Fig. 10 is a side view of a knife frame adapted to have mounted thereon a covering unit such as shown in Fig. 7;

Fig. 11 is a view similar to Fig. 8 of a cover-

2

ering unit embodying still another modified form of my invention;

Fig. 12 is a side view of a knife frame adapted to receive a covering unit such as shown in Fig. 11;

Figs. 13 and 14 are views similar to Fig. 11 covering yet other modified forms of my invention;

Fig. 15 is a figure similar to Fig. 3 of a covering unit embodying yet a further modified form of my invention; and

Figs. 16 and 17 are sectional views taken substantially along the lines 16—16 and 17—17, respectively, of Fig. 15.

In general, I achieve the several objects of my invention by providing a pre-assembled ornamental covering unit which includes an ornamental cover plate whose configuration, essentially, corresponds to the configuration of the knife frame on which the covering unit is to be mounted. This covering plate is provided with one or more bolsters not connected to each other by any metal member integral therewith. The bolsters overlie portions of the cover plate being disposed in certain regions, e. g., at the ends of the cover plate, in a manner well known to the art. Said bolsters are held to the cover plate by means integral with the bolsters so that the bolsters and cover plate can be assembled as a unit before they are mounted and attached to the frame of a knife.

Preferably, means also is included which is integral with the bolsters and is adapted to secure the bolsters, and therefore the covering unit, to a knife frame. Because of the usual location of the bolsters at the ends of the cover plate, which conventionally is elongated, this mounting means for the covering unit is subject to the defect that the center of the cover plate tends to move away from the knife frame. Such defect can be quite serious, commercially, under certain conditions, as, for example, when the cover plate is somewhat flexible and the knife frame is a little too short for the covering unit. If, under these circumstances, the bolsters are forced together during mounting of the covering unit on the knife plate, they cause the cover plate to spring away from the knife frame. This defect can occur frequently since the cover plates usually are made from a synthetic plastic and therefore are unable to resist compressive stress without buckling to leave a slight but undesirable space between the cover plate and knife frame near the center of the covering unit. In addition, the cover plates occasionally are of such

configurations that they tend to be weak in certain areas and thus tend to crack or twist in these areas. Furthermore, during long or hard use the cover plates sometimes warp between the bolsters.

Pursuant to the present invention, these defects and others are avoided by reinforcing the cover plate externally at one or more points intermediate the bolsters. The reinforcement can be accomplished in various manners, as will be seen hereinafter, and, in general, is achieved by employing a stiffening member, independent of the knife frame, which member is disposed beneath and connected to at least that portion of the cover plate between the bolsters.

Referring now in detail to the drawings, and more particularly to Figs. 1 through 6, 30 denotes a jackknife having any suitable type of frame 32. Said frame comprises a set of blades 34, 36, 38 of which the two knife blades 34, 36 are pivotally mounted on a rivet 40, by and connecting a pair of parallel upper and lower lining plates 42, 44. An intermediate plate 46 separates the knife blades 34, 36. The other blade 38, as illustrated, comprises a reamer and is pivotally mounted on a rivet 48, secured to the upper and lower mounting plates at the opposite end of the knife frame. The usual heavy block springs 50, 52 are provided to hold the blades in either closed or open position. As is customary in the art, a central rivet 54 (not shown) maintains the centers of the various elements of the knife frame in proper position. The heads of all the rivets, i. e. the rivets 40, 48 and 54 extend above the surface of the lining plates 42, 44.

I provide an ornamental covering unit 90 to overlie the otherwise exposed surface of each of the outer lining plates 42, 44. Inasmuch as said lining plates are identical in each of the forms of my invention herein set forth, only one plate will be described for each form. The covering includes an ornamental elongated cover plate 60 and a pair of separate bolsters 62, 64. The cover plate is made from any suitable decorative material such, for example, as celluloid, synthetic resins of the phenol or urea formaldehyde condensation type, cellulose acetate, cellulose acetate butyrate, styrene, polyacrylic resins, hard rubber, or the like, and is of appreciable thickness so that when not abnormally stressed, it will maintain its shape. The exposed longitudinal edges of the cover plate are of substantially the same contour as the underlying edges of the lining plates 42, 44.

The underside of the cover plate is provided with suitable indentations 66, 68, 70, 72 to accommodate the heads of the various rivets, and other indentations whose positions and purpose will be described hereinafter.

The upper side or outer surface of the cover plate is fashioned, either by a material removing operation or during the molding thereof, with a set of markings which cause the plate to resemble a hand-tooled stag knife handle. These markings may comprise a large number of shallow elongated indentations which taper toward the opposite ends thereof and run in a direction generally parallel to the longitudinal axis of the cover plate.

The bolsters 62, 64 preferably are fabricated from thin strong material such as sheet metal. One bolster is disposed over each end of the elongated ornamental cover plate. Said bolsters are so dimensioned with respect to the ends of the ornamental cover plate that the outer surfaces

of the bolsters constitute smooth, flush continuations of the outer surface of the cover plate adjacent the ends thereof. In addition, the edges of the bolsters are a smooth flush continuation of the longitudinal edges of the cover plate. Moreover, the edges of the bolster, like the longitudinal edges of the cover plate, substantially conform to the contour of the underlying edges of the lining plate. To these ends, the portions 10 of the cover plate which are overlain by the bolsters are reduced in size by an amount substantially equal to the thickness of the sheet metal comprising the bolsters.

I also provide means integral with the bolsters 15 for positively and firmly attaching the same to the cover plate. Said means comprises an element, herein shown in the form of an integral tine or projection 74, extending from the center of the edge of the bolster which runs across the cover plate. The tine passes through an opening 76 in the cover plate and is bent over to lie in a recess 78 on the underside of said plate where said tine is firmly clinched in position. It will be appreciated from inspection of Fig. 4 that 20 when the tines are disposed in the manner just described, the two bolsters will be tightly and permanently attached to the decorative cover plate and when said cover plate is mounted on the knife frame, these tines will be substantially concealed.

Suitable means also is provided for attaching the bolsters 62, 64 to the knife frame. For this purpose there is employed another integral projection or tine 80 which projects from the 25 narrow end or tip of the bolster. Said projection, after the bolsters and cover plate have been assembled into the unit shown in Fig. 4, extends away from the bottom surface of the unit.

The knife frame upon which this type of unit 40 is mounted is provided with a pair of pockets 82 at each end of the lining plates, these pockets being so positioned and constructed that they are adapted to receive the projections 80. The projections are folded into the pockets after the 45 pre-assembled unit has been properly positioned upon the knife frame. As seen from Figs. 1 and 4, the projections 80 after being folded to lie within their associated pockets are disposed almost entirely within the periphery of the bolsters 50 and only will be barely noticeable upon the exterior of the knife. Because of the elevation of the pockets above the general level of the lining plates, the recess 78 which receives the clinched projection 74 is extended to accommodate said 55 pockets.

Pursuant to my invention, the covering unit includes means for reinforcing the same whereby the portion of said cover plate intermediate the bolsters is stiffened. The cover plate 60 is specially shaped to receive the reinforcing means. To this end the cover plate is formed with a channel 92 in its undersurface, the channel extending from the recess 78 at one end of the cover plate to the like recess at the other end of the cover plate. Said reinforcing means constitutes a strip 94 of sheet steel or the like strong material which is fully received in the channel 92. Suitable means is included to hold this strip in place flat against the back of the cover plate. Such means may comprise a pair of rivets 96, 98, which extend through openings 100 in the cover plate and are headed over on the underside of the strip 94.

The strip may include means to permanently 70 and rigidly connect the strip to a knife frame.

Such means, in the form of the invention under discussion comprises a tine 102 struck out from the strip somewhere between its ends, optionally near the center of the strip as shown. This tine is passed through an opening 104 in the upper lining plate 42 and the tip thereof bent over to lie against the interior surface of the lining plate. Preferably, the tip is directed toward the block springs 58, 52, so as not to interfere with closing of the blades. If the blades are of such type that they fill up the blade compartment in the region where the tines are bent over, the openings 104 may form parts of pockets which accommodate the bent over tips of the tines, much in the same fashion that the pockets 82 accommodate the tines 80.

In the remaining figures I have shown covering units embodying various modified forms of my invention wherein other arrangements are provided for stiffening the portion of the cover plate between the bolsters. Basically, the cover plate and bolsters of these modified forms are similar to those of the covering unit already described, and the knife frames on which these modified covering units are adapted to be mounted likewise are generally similar to the knife frame described with reference to the first embodiment of my invention. Accordingly, in order to shorten the description of these modified covering units and of the parts of the knife frames to which they are attached, all elements of the covering units and knife frames which are substantially similar to the elements already described will be denoted by the same reference numerals.

Instead of holding the strip 94 in place with rivets, the tine 74 can be employed to perform such function, as shown in the covering unit 110 which is illustrated in Figs. 7 through 10. In this covering unit the groove 92 accommodates a sheet metal strip 112 which is longer and somewhat heavier than the strip 94 to enable it to extend over the through openings 76 which pass the tines 74. Depressed areas 113 of said strip 112 are provided with apertures 114 in registry with the openings 76 so that the tines 74 can be clenched against the exposed undersurface of the strip 112 and thereby hold the strip against the undersurface of the cover plate, in addition to holding the bolsters against the top surface of said cover plate. The strip 112 is provided with a tine 116 which is identical to the tine 102 and is adapted to be received in the opening 104 in the lining plate (see Fig. 10). After insertion through the lining plate, the tip of the tine 116 is bent over to hold the center of the ornamental covering unit against the knife frame.

The covering unit 120 shown in Figs. 11 and 12 employs a different arrangement for holding down its center to the knife frame. Instead of having the through opening 104, the outer lining plate is provided with an integral projecting spike 122, which, during assembly of the knife, is embedded in the underside of the cover plate 60. Optionally, the cover plate can be formed with an indentation 124 in its undersurface slightly smaller than the spike in order to facilitate embedding of the latter. The cover plate may be preheated for the same purpose, if made from a thermoplastic substance such, for instance, as cellulose acetate butyrate.

Covering units 130 and 135 embodying other modified forms of my invention are shown in Figs. 13 and 14, respectively. These units differ from the units 110 illustrated in Figs. 3 and 7 respectively in that the tines 102 and 116 are

omitted, reliance being placed on the stiffness of the strips 94, 112 to reinforce the cover plate 60.

Yet another modified form of my invention is disclosed in the ornamental covering unit 140 shown in Figs. 15 through 17. In this unit, reinforcement of the cover plate 60 is obtained by providing a metal plate 142 which underlies substantially the entire undersurface of the cover plate. Said metal plate has its peripheral edges in registry with the longitudinal edges of the cover plate, and with the side edges of the bolsters 62, 64. The metal plate has notches 144 at its opposite ends which overlie the recesses 78, and are provided in order to accommodate the pockets 82 in the outer lining plate. Depressed straps 146 integral with the metal plate 142 bridge the notches 144 near their inner closed ends whereby to provide slots 148 which receive the tines 74. When the tips of said tines are turned over, they serve to hold the metal plate 142 against the undersurface of the cover plate.

It thus will be seen that I have provided knives which achieve the several objects of my invention and are well adapted to meet the conditions of practical use.

As various possible embodiments might be made of the above invention, and as various changes might be made in the embodiments above set forth, it is to be understood that all matter herein described or shown in the accompanying drawings is to be interpreted as illustrative and not in a limiting sense.

Having thus described my invention, I claim as new and desire to secure by Letters Patent:

- 35 1. A pre-assembled ornamental cover unit for a knife frame having an outer lining plate, said unit comprising a pair of separate bolsters, an elongated, thick, preformed, ornamental cover plate, whose longitudinal edges are adapted to be arranged coextensively with the corresponding longitudinal edges of the knife frame, each of said bolsters having integral attaching means which positively and firmly holds said bolster to said cover plate, a stiffening member beneath said cover plate and adapted to be disposed on the outer surface of said lining plate, said stiffening member having a portion extending between said bolsters, and means to secure said stiffening member to said cover plate.
- 40 2. A pre-assembled ornamental cover unit for a knife frame having an outer lining plate, said unit comprising a pair of separate bolsters, an elongated, thick, preformed, ornamental cover plate, whose longitudinal edges are adapted to be arranged coextensively with the corresponding longitudinal edges of the knife frame, each of said bolsters having integral attaching means which positively and firmly holds said bolster to said cover plate, a stiffening member beneath said cover plate and adapted to be disposed on the outer surface of said lining plate, said stiffening member having a portion extending between said bolsters, and means to secure said stiffening member to said cover plate.
- 45 3. A pre-assembled ornamental cover unit for a knife frame having an outer lining plate, said unit comprising a pair of separate bolsters, an elongated, thick, preformed, ornamental cover plate, whose longitudinal edges are adapted to be arranged coextensively with the corresponding longitudinal edges of the knife frame, each of said bolsters having integral attaching means which positively and firmly holds said bolster to said cover plate, a stiffening member beneath said cover plate and adapted to be disposed on the outer surface of said lining plate, said stiffening member having a portion extending between said bolsters, and means to secure said stiffening member to said cover plate at at least one point intermediate the bolsters.
- 50 4. In combination in a knife including a knife frame having an outer lining plate, an elongated, thick preformed cover plate, a pair of separate bolsters, one overlying each end of the cover plate, each of said bolsters having integral attaching means which positively and firmly holds said bolster to said cover plate, each of said bolsters having integral attaching means which positively and firmly holds said bolster to the knife frame, a stiffening member beneath said
- 55 5. In combination in a knife including a knife frame having an outer lining plate, an elongated, thick preformed cover plate, a pair of separate bolsters, one overlying each end of the cover plate, each of said bolsters having integral attaching means which positively and firmly holds said bolster to said cover plate, each of said bolsters having integral attaching means which positively and firmly holds said bolster to the knife frame, a stiffening member beneath said
- 60 6. In combination in a knife including a knife frame having an outer lining plate, an elongated, thick preformed cover plate, a pair of separate bolsters, one overlying each end of the cover plate, each of said bolsters having integral attaching means which positively and firmly holds said bolster to said cover plate, each of said bolsters having integral attaching means which positively and firmly holds said bolster to the knife frame, a stiffening member beneath said
- 65 7. In combination in a knife including a knife frame having an outer lining plate, an elongated, thick preformed cover plate, a pair of separate bolsters, one overlying each end of the cover plate, each of said bolsters having integral attaching means which positively and firmly holds said bolster to said cover plate, each of said bolsters having integral attaching means which positively and firmly holds said bolster to the knife frame, a stiffening member beneath said
- 70 8. In combination in a knife including a knife frame having an outer lining plate, an elongated, thick preformed cover plate, a pair of separate bolsters, one overlying each end of the cover plate, each of said bolsters having integral attaching means which positively and firmly holds said bolster to said cover plate, each of said bolsters having integral attaching means which positively and firmly holds said bolster to the knife frame, a stiffening member beneath said
- 75 9. In combination in a knife including a knife frame having an outer lining plate, an elongated, thick preformed cover plate, a pair of separate bolsters, one overlying each end of the cover plate, each of said bolsters having integral attaching means which positively and firmly holds said bolster to said cover plate, each of said bolsters having integral attaching means which positively and firmly holds said bolster to the knife frame, a stiffening member beneath said

cover plate having a portion extending between the bolsters, said stiffening member being disposed on the outer surface of said lining plate, and means securing said stiffening member to said cover plate.

4. A combination as set forth in claim 3 where-in the means for holding the bolsters to the cover plate secures the stiffening member to the cover plate.

5. In combination with a knife comprising a knife frame having an outer lining plate, a covering unit including an elongated, thick, preformed, ornamental cover plate, a pair of separate sheet metal bolsters whose longitudinal edges are arranged coextensively with the corresponding edges of the knife frame, said bolsters overlying the ends of said cover plate, means to secure the bolsters to the cover plate, means to secure the bolsters to the knife frame, a stiffening member beneath said cover plate having a portion extending between the bolsters, said stiffening member being disposed on the outer surface of said lining plate, and rivets to secure said stiffening member to said cover plate.

6. In combination with a knife comprising a knife frame having an outer lining plate, a covering unit including an elongated, thick, preformed, ornamental cover plate, a pair of separate sheet metal bolsters whose longitudinal edges are arranged coextensively with the corresponding edges of the knife frame, said bolsters overlying the ends of said cover plate, means to secure the bolsters to the cover plate, means to secure the bolsters to the knife frame, and a stiffening member beneath said cover plate having a portion extending between said bolsters, said stiffening member being disposed on the outer surface of said lining plate, the means for securing said bolsters to said cover plate also serving to secure the stiffening member to the cover plate.

7. In combination with a knife comprising a knife frame having outer lining plates, a covering unit including an elongated, thick, preformed, ornamental cover plate, a pair of separate sheet metal bolsters whose longitudinal edges are arranged coextensively with the corresponding edges of the knife frame, said bolsters overlying the ends of said cover plate, means to secure the bolsters to the cover plate, means to secure the

bolsters to the knife frame, said cover plate being formed with a groove along its undersurface, a stiffening member lying in said groove and extending between said bolsters, and means to secure said stiffening member to said cover plate.

5. In combination with a knife comprising a knife frame having outer lining plates, a covering unit including an elongated, thick, preformed, ornamental cover plate, a pair of separate sheet metal bolsters whose longitudinal edges are arranged coextensively with the corresponding edges of the knife frame, said bolsters overlying the ends of said cover plate, means to secure the bolsters to the cover plate, means to secure the bolsters to the knife frame, a stiffening member beneath said cover plate, and means to secure said stiffening member to said cover plate, said stiffening member having a projection which is received in an opening in an outer lining plate, the tip of said projection being bent to lie against the inner surface of the lining plate.

8. In combination with a knife comprising a knife frame having an outer lining plate, a covering unit including an elongated, thick, preformed, ornamental cover plate, a pair of separate sheet metal bolsters whose longitudinal edges are arranged coextensively with the corresponding edges of the knife frame, said bolsters overlying the ends of said cover plate, means to secure the bolsters to the cover plate, means to secure the bolsters to the knife frame, a stiffening plate interposed between the undersurface of the cover plate and the outer surface of the lining plate, the edges of said stiffening plate coinciding with the longitudinal edges of the cover plate, and means to secure said stiffening plate to the cover plate.

HENRY VOSSLER.
